[57] CLAIM

The ornamental design for a heat exchanger with gas venting means, as shown and described.

DESCRIPTION

FIG. 1 is a front elevation of a heat exchanger with gas venting means showing our new design;
FIG. 2 is a left side elevation thereof;
FIG. 3 is a right side elevation thereof;
FIG. 4 is a top plan thereof; and
FIG. 5 is a bottom plan thereof.

*Fig. 4.**Fig. 2.**Fig. 1.**Fig. 3.**Fig. 5.*
